US00D789476S

(12) **United States Design Patent** (10) **Patent No.:** **US D789,476 S**
Dustin et al. (45) **Date of Patent:** **** Jun. 13, 2017**

(54) **SUBMACHINE GUN**(71) Applicant: **Sig Sauer, Inc.**, Newington, NH (US)(72) Inventors: **Bryan C. Dustin**, Strafford, NH (US);
David Steimke, Epping, NH (US);
Mark Wingate, New Durham, NH (US)(73) Assignee: **Sig Sauer, Inc.**, Newington, NH (US)(**) Term: **15 Years**(21) Appl. No.: **29/551,645**(22) Filed: **Jan. 15, 2016**(51) LOC (10) Cl. **22-01**

(52) U.S. Cl.

USPC ..... **D22/103**(58) **Field of Classification Search**USPC D22/103, 108; D21/572-575
CPC F41A 9/01-9/79; F41A 3/00; F41A 17/00-17/38

CLAIM

The ornamental design for a submachine gun, as shown and described.

DESCRIPTION

FIG. 1 is a left elevation view of a submachine gun showing the design;

FIG. 2 is a right elevation view thereof;

FIG. 3 is a rear elevation view thereof;

FIG. 4 is a front elevation view thereof;

FIG. 5 is a top plan view thereof;

FIG. 6 is a bottom plan view thereof; and,

FIG. 7 is a rear perspective view thereof.

Broken lines in the drawings are for the purpose of illustrating environmental structure and form no part of the claimed design.
